SHINGLE

Raymon W. Clough, Cranston, R. I.

Application June 19, 1933, Serial No. 676,469

2 Claims. (Cl. 108—7)

This invention relates to shingles of the type especially designed for laying up in butted Dutch lap courses and particularly useful for siding but not limited to that use.

5 The earliest Dutch lap shingle was rectangular and in laying up was applied with its longer dimension horizontal, the watershed being formed by a uniform end lap for each shingle and a uniform head lap for each course. The 10 joints caused by the end laps in laying up shingles by this method are staggered throughout the successive courses by butting the head lapped shingle in the course above against the end edge of the side lapped shingle in the course 15 below. The United States patent to Gambs No. 595,618, December 14, 1897 is illustrative of butted Dutch lapped shingles.

The most economical size of rectangular shingles for butted Dutch lap laying to obtain an exposure of each shingle that gives the best appearance to the house is 8" high by 16" wide and experience has shown that the best results and greatest saving of stock is obtained by laying with a 1" head lap and a 2" end lap. Each 20 shingle thus has the preselected exposure of 7" x 14". Siding laid in butted Dutch lap courses with such shingles, while requiring less stock (only 131 sq. ft. of material to a square) than is required for wood shingles of irregular 25 size, has not proved especially popular because the relatively narrow end lap as compared to the width of the exposure causes the exposed edges of the end laps, which come into vertical alignment only at each 7th course, to approximate an inclined line, thus giving a slanting or 30 leaning appearance to a house wall.

This appearance can be avoided by increasing the end lap, but if the desired 7" x 14" exposure is to be preserved this means so much more 35 stock to a square (for lapping in thirds 153 sq. ft.; in halves 172 sq. ft.) that this change in the manner of laying, with rectangular shingles, is prohibitive.

It is the purpose of this invention to provide 40 a shingle for butted Dutch lap laying with the desired 7" x 14" exposure by means of which the courses can be lapped in thirds of the exposure, thus spacing these joints according to 45 accepted end lap practice adjudged sufficient to overcome the slanting appearance which is 50 characteristic of the earlier Dutch lap method of laying, and with no appreciable increase in the amount of stock required to cover a square, or the courses can be lapped in halves of the 55 exposure with only a slight increase in the

amount of stock required for a square and even then less than the 153 sq. ft. required for lapping in thirds with rectangular shingles.

An important feature of the present invention resides in the complete preservation of a tight watershed where the shingles are end lapped notwithstanding the apparent reduction in the amount of material required for a square over the use of rectangular shingles when lapped in either thirds or halves. In carrying out the 10 invention for the purposes described the shingle consists of a right-angular trapezoid and the oblique end thereof is specially formed, taking account of the fact that the shorter side edge forms the head or top edge of the shingle, to 15 preserve an extent or length of end lap that will provide a reliable watershed.

With the above and other objects in view which will appear as the description proceeds, the invention comprises the novel shingle and a 20 butted Dutch lapped siding composed thereof substantially as hereinafter described and more particularly as defined by the appended claims, it being understood that such changes in the 25 precise embodiment of the invention as herein disclosed may be made as come within the scope of the claims.

Reference may be had to the accompanying drawing illustrating the preferred embodiment 30 of the invention, in which:

Figure 1 is a view showing the novel shingle type of this invention layed in butted Dutch lap courses to produce a siding;

Fig. 2 is a plan view of a strip of material of shingle height showing the method of cutting 35 for lapping in thirds; and

Fig. 3 is a view of a shingle dimensioned for lapping in halves and illustrating preservation of the watershed.

In the accompanying drawing Fig. 2 illustrates 40 the method of preparing the preferred form of the novel shingle whereby the advantage of end lapping the exposure in thirds may be obtained from substantially the same amount of stock as heretofore used for rectangular shingles which 45 give an undesirable slanting effect to the siding or roof.

In its broader aspect the shingle is of trapezoidal form having parallel side edges 10 and 50 12 of which one is longer than the other and forms the bottom edge of the shingle when layed. One end edge 13 is square with the side edges and the other end edge 15 is generally oblique. This form will be identified herein as a right- 55 angular trapezoid. Fig. 2 represents a rectan-

5 gular blank 16 sufficient for two shingles, being the full height of the shingle in its shorter dimension and equal to the sum of the long and short side edges in its longer dimension. Designating the top side edge mn the blank 16 is severed diagonally between a point at a distance mn from one end on one edge and a point at a distance mn from the other end on the other edge. As will appear presently the most efficient 10 but not necessarily the only boundary for the oblique end 15 of the right-angular trapezoid to be produced is in the form of an ogee curve and it is of importance, when this boundary is used, that the convex portion of the curve be 15 adjacent the shorter side edge 10, that is, the curve is a cyma reversa with respect to the top edge of the shingle. The material from which the shingles are made may be such that it breaks more or less easily and for such material 20 it is desirable to avoid sharp corners such as would occur if an oblique cut on the ogee curve extended completely across the blank 16. Accordingly it is desirable to provide the oblique end edge 15 with a pair of short in-turned shoulders 18 and 19 adjoining the top and bottom edges respectively. These shoulders are connected by a central portion of the oblique end edge and form blunt terminals therefor, not easily chipped or broken. 25

30 Severing the blank 16 in the manner described yields two complete shingles from a blank that is shorter than double the long bottom edge length of a shingle by the difference in length between the top and bottom edges, designated 35 by n on Fig. 2. In practice a sufficient number of this novel shingle, to cover a square layed up in thirds in butted Dutch lapped courses having an exposure of 7" x 14", can be cut from 134 sq. ft. of stock as against 131 sq. ft. for the 40 less attractive Dutch lap laying with rectangular shingles. For laying in halves, which requires a longer bottom edge 12, only 10 sq. ft. of additional stock is required. Thus there is a most favorable cost comparison for the new shingles 45 over the old.

50 Right angular trapezoidal shingles as thus produced for end lapping in thirds on the exposure of the subjacent shingles are layed up in the manner illustrated by Fig. 1. Considering that Fig. 1 represents siding, in laying horizontally from left to right, a lower course shingle 20 has its right-angular end 13 aligned with the corner of the house and is end lapped a distance n by a shingle 20' which shingle 20' is similarly 55 end lapped by a third shingle 20'' and so on across the wall to be covered. For the second course a shingle 20 is shortened to fit between the end edge 13 of shingle 20' in the lower course and the corner of the house and is head lapped on the first course shingle 20. For Dutch lap laying with shingles of the size now being considered the head lap is usually 1". If the shoulders 18 and 19 are cut $1/2$ " deep then the butting described will bring the lower shoulder 60 65 19 of the second course shingle 20 just below the upper shoulder 18 of the first course shingle 20'. After completing the second course other courses are layed in like manner. Those skilled in the art will recognize that a siding laid up as 70 illustrated by Fig. 1 will bring the exposed edges of the end laps into vertical alignment every 3rd course thus avoiding the leaning appearance of the older siding while, at the same time, utilizing

5 ing an end lap within the accepted standard that is commercial practice. Securing nails are driven as in Dutch lap laying with rectangular shingles. It will be observed that the top shoulders 18 provide a gage for end lapping and the shingles do not need to be pre-punched with nail holes to insure a uniform end lap throughout a course.

10 Especial attention is called to the provision of a reliable siding watershed, where three shingles overlap, notwithstanding the use of the trapezoidal form of shingle. Referring to Fig. 3 the dotted line $a-a$ may indicate the depth of the head lap of shingles 20 and 20' of the second course on shingles 20 and 20' of the first course. 15 Owing to the use of a cyma reversa curve, as described, the material on first course shingle 20 builds out quickly from the top shoulder 18 and provides a substantial length w at the critical point of overlap. In Fig. 3 the dot and dash line 20 shows the end boundary of a geometrical trapezoid which is within the scope of this invention but is less efficient than an ogee end boundary as may be seen by comparing the length 25 of the critical overlap w' with that of w .

While the foregoing description has, for illustration, used a particular size of shingle, those skilled in the art will recognize that other sizes may be used and the same advantages obtained by applying the underlying principle of 30 production. Thus if the top edge 10 has a length mn (Fig. 2) and the width of the end lap on the bottom edge 12 is n then the width of the shingle at the bottom is always $mn+n$. For laying in thirds (Fig. 1) mn must be three 35 times as long as n and for laying in halves (shingle of Fig. 3) twice as long. For such laying of any size a shingle, m must always be an integer multiple of n .

40 The nature and scope of the invention having been indicated and the preferred embodiment having been specifically described, what is claimed as new, is:—

45 1. A shingle having two parallel side edges one of which, constituting the bottom edge, is longer than the other, one squared end, and its other end formed by a short in-turned shoulder adjoining each side edge the inner ends of which are connected by a cyma reversa curve extending from the said shoulder at the shorter side edge to said shoulder at the longer side edge.

50 2. Shingled siding and the like layed up in horizontal courses with shingles of trapezoidal form having parallel top and bottom edges the latter being longer than the former, having one right angular end and having the other end bounded by in-turned top and bottom shoulders connected by a cyma reversa curve, each shingle of each course having its right-angular end lapped as far as said top shoulder upon the 60 oblique end of the next shingle in its course, and each shingle of a course above the lowest having its bottom shoulder butted against the right-angular end of an overlapping shingle in the course below, the point of contact being below the top shoulder of the overlapped shingle in said course below, thus head lapping two adjacent shingles in said course below, the upper convex portion of said cyma reversa providing a watershed extending laterally a substantial 65 distance beneath both said end lap and said head lap.
